UNITED STATES PATENT OFFICE.

ANDREW HACKNEY, OF PORTAGEVILLE, MISSOURI.

BARBECUE-STOVE.

1,250,861.

Specification of Letters Patent. Patented Dec. 18, 1917.

Application filed February 17, 1917. Serial No. 149,273.

To all whom it may concern:

Be it known that I, ANDREW HACKNEY, a citizen of the United States, residing at Portageville, in the county of New Madrid 5 and State of Missouri, have invented new and useful Improvements in Barbecue-Stoves, of which the following is a specification.

This invention relates to portable stoves.

10 The object of the present invention is to provide a stove which may be readily transported from place to place and easily and quickly set up in position for use.

Another object of the invention is to provide a stove of the above character which is primarily intended for use at barbecues and is capable of roasting a hog or other animal which may be placed thereon, the said stove being so constructed that when not in use 20 may be readily taken apart and conveniently packed for storage or shipment.

With the above and other objects in view the invention consists of the following novel combination and arrangement of parts, 25 hereinafter more fully described and illustrated in the accompanying drawings; in which;

Figure 1 is a perspective view of the improved stove set up in position for use;

30 Fig. 2 is a transverse sectional view of the same;

Fig. 3 is a detailed longitudinal sectional view taken through a portion of one end of the stove and illustrating the manner of engagement of the locking lug with the end section;

Fig. 4 is a detailed sectional view on the line 4—4 of Fig. 2.

Referring specifically to the drawings, 40 wherein is shown the preferred embodiment of the invention, the numeral 1 designates the side sections of the stove, each of said sections being formed alike. The sections 1 have secured at each end by means of a 45 curled portion 2 supporting legs 3, these legs being slightly longer than the height of the side sections in order that the stove may be supported at a convenient distance above the ground. The side sections are provided 50 with longitudinal flanges 4, which form supports for the bottom section 5 and the

end sections 6, the said bottom section resting upon the supporting flanges 4, while the end sections rest upon the end of the bottom section. Each of the end sections 6 are provided with openings 7 which are adapted to be closed by means of hinged doors 8, these openings providing means for the insertion of fuel into the stove, while the doors regulate the draft therethrough. 60

The stove is further provided with a removable grate section 9, the said section comprising end bars 10 and longitudinal connecting bars 11, the whole comprising a rectangular frame provided with intermediate longitudinally extending grate bars. This grate in addition to providing means for supporting the animal above the fire also provides means for locking the various sections of the stove in position for use. To 70 this end the side sections 1 are formed with locking flanges 12, these flanges being formed by turning over the upper longitudinal edges of the sections 1, in order that they may engage the outermost longitudinal bars 11 of 75 the grate. The grate is further provided at each end thereof with locking lugs 13, the said lugs extending downwardly from the end bars 10 and engaging the inner upper edges of the end sections 6 for the purpose 80 of preventing the inward movement of these sections. The end sections 6 are held against outward movement by means of the portions 2 forming shoulders 14 against which the end sections 6 are adapted to engage. 85

It is thought from the foregoing description when taken in connection with the accompanying drawings that the construction, operation and advantages of the invention will be apparent and that a further description is unnecessary. 90

Having described the invention, what I claim, is;

1. A portable stove comprising a rectangular receptacle formed of separable side 95 and end sections, a removable bottom section, supporting legs carried by said side sections, said legs being secured to said side sections by curling the ends of the said sections around the same, the curled portions 100 thus formed forming retaining shoulders for the end sections, a removable grate section

and means whereby said grate section will lock the various parts of the stove in position for use.

2. A portable stove comprising a rectangular receptacle formed of separable side and end sections, inturned locking flanges provided along the upper edge of each of the side sections, a removable bottom section, a

removable grate section engageable with the locking flanges of the side sections and lugs 10 carried by each end of the grate section for engagement with the end sections, whereby, said grate section will lock the side and end sections in set-up position.

In testimony whereof I affix my signature, 15
ANDREW HACKNEY.
